UNITED STATES PATENT OFFICE

JOHN J. WHITE, OF CHICAGO, ILLINOIS, ASSIGNOR TO THE FLORSHEIM SHOE CO., OF CHICAGO, ILLINOIS, A CORPORATION OF ILLINOIS

MOCCASIN

Application filed January 5, 1931. Serial No. 506,767.

The invention relates to moccasins and has as its primary object the provision of a moccasin which is of improved construction and may be manufactured readily without 5 sewing the seams therein by hand.

A moccasin embodying a preferred form of the invention is formed from a vamp, a front, quarters, etc., the construction being such that the edges of the vamp are joined 10 to each other at the bottom of the shoe by a seam which is readily sewed by machine and which extends more or less centrally of the shoe from the toe thereof to a point at the breast of the heel or adjacent it.

15 The improved method of manufacturing the moccasin permits the vamp to be molded on a last and have the edges described above overlap each other in such manner that excess material can be cut away by a single 20 stroke of a cutting tool. The improved method makes it unnecessary, in the preferred embodiment of the invention, to provide seams extending laterally from the substantially central seam described above.

25 A moccasin constructed by practicing the improved method is shapely and durable, and the material from which it is formed does not gather in bunches, etc., to annoy the wearer.

30 The improved method effects a saving in labor. Part of the saving is due to the fact that the vamp is easily given the correct size and shape without cutting blanks therefor to the exact size and shape. The excess material is simply cut away prior to the sewing operation.

35 Other objects and advantages of the invention will become apparent as the following detailed description progresses, reference 40 being had to the accompanying drawings, wherein:

Figure 1 is a side elevation of a moccasin which embodies the invention.

45 Fig. 2 is a section taken on line 2--2 of Fig. 1.

Fig. 3 is a section taken on line 3--3 of Fig. 1.

Fig. 4 is a section taken on line 4--4 of Fig. 1.

50 Fig. 5 is a side elevation of the upper por-

tion of the moccasin before the sole is attached thereto.

Fig. 6 is a bottom plan view of the upper portion shown in Fig. 5.

Fig. 7 is a bottom plan view of the upper 55 portion of the moccasin as it appears upon a last before it has been completed.

Fig. 8 is an elevation of a plug which is placed within the moccasin at the front end thereof to cover a relatively small opening 60 left in the bottom portion of the vamp.

Fig. 9 is a blank from which the vamp for the improved moccasin is formed.

Figs. 10 and 11 are the blanks from which the quarters of the improved moccasin are 65 formed, and

Fig. 12 is a blank from which the front of the improved moccasin is formed.

Referring to the drawings wherein a preferred form of the invention is illustrated, 70 it will be noted that the moccasin comprises a vamp A; quarters B and B'; a foxing portion C secured to the quarters B and B'; a toe cap D; a leather sole E, a sole F formed of crepe rubber; a plug G; an inner sole 75 member H, and a tongue J which is secured to the rear edge of the front D.

Referring to Figs. 1 to 6, inclusive, it will be noted that the toe cap D is secured to the vamp A by stitches 15, which extend through a folded edge of the vamp. The edges of the vamp at the bottom of the shoe abut each other and are secured to each other by stitches 16 which may be made by a sewing machine, just as the stitches 15 may be made 85 by a sewing machine. The quarters B and B' are secured to the rear edges of the vamp A by machine stitches 17, the rear edges of the quarters being secured to the front edges of the foxing portion C by machine stitches 90 18.

The inner sole H is preferably formed from leather and secured to the foxing portion C and the quarters B and B' by any suitable means, such as nails 20 (see Fig. 6). 95

The leather sole E is secured to the upper portion of the moccasin by machine stitches 21, which also extend through the plug G, the plug G being preferably cemented to the inner surface of the vamp. 100

Referring to Fig. 9, wherein a blank 25 for the vamp A is shown, it will be noted that the blank 25 is provided with an excess of material in the form of flaps 26 which are spaced from each other by a relatively wide notch 27 cut in the blank. The cut forming the bottom of the notch 27 extends a short distance into both of the flaps 26, as indicated at 28. Disposed opposite the notch 27 on the other side of the blank 25 is an arcuate edge 29 to which the forward edge 30 of the front is sewed, the lateral edges of the toe cap D being sewed to edges 31 of the blank 25, which edges 31 extend substantially tangentially from the arcuate edge 29. The stitches 15 which secure the toe cap D to the vamp A extend along the edges 29 and 31 between two cuts or slits 33 made in the blank 25, this construction being employed to provide a folded edge upon the vamp where it meets the front D.

In Figs. 10 and 11, blanks 35 and 36 for forming the quarters B and B', respectively, are shown. The forward edges 35a and 36a are secured to the rear edges 25a of the blank 25 by the stitches 17, the back edges 35b and 36b of the blanks 35 and 36 being secured to the heel portion C by the stitches 18.

In practicing the improved method, the blank 25 of the vamp A is stitched to the front D and to the blanks 35 and 36 which form the quarters B and B', the heel portion C being secured to the rear edges of the quarters as described above. The inner sole member H is then tacked to a last 40 to form the heel-seat of the moccasin (see Fig. 7) and the assembled front, assembled quarters and foxing are drawn over the last 40, these assembled parts being in a wet condition. The assembled structure is molded over, or shaped to the last, as illustrated in Fig. 7, so that the flap portions 26 of the vamp A overlap each other. The vamp is then secured in this position to the last 40 by tacks 41, or the equivalent and permitted to remain in this position until it has dried. A knife or any other suitable cutting tool is then drawn through the overlapping flaps 26 along a line extending longitudinally of the moccasin and, more or less, centrally thereof to provide the abutting edges which are subsequently secured to each other by the stitches 16, described above. The foxing portion is tacked to the heel-seat or inner sole member H by the tacks or nails 20. After the upper portion of the moccasin has been removed from the last 40, the plug G is cemented to the inner surface of the vamp A to cover a relatively small aperture 43 which appears at the front end of the seam formed by the stitches 16 (see Fig. 6). The leather sole E may then be secured to the upper portion of the moccasin by the stitches

21 after which the sole F is secured to the leather sole E.

It will be readily understood by those skilled in the art that the invention is not limited to the use of a foxing member C of the type shown in the drawings, as the quarters may be made to extend around the heel of the shoe, or any other suitable construction may be employed. It is also to be understood that any suitable sole may be employed and that the invention is limited to the structure which is shown only to the extent indicated in the appended claims.

Moccasins embodying the invention may be manufactured relatively inexpensively as it is not necessary to sew seams therein by hand, although some or all of the seams may be sewed by hand if it is so desired. The improved construction of the vamp insures that the moccasin will retain its shape and that the moccasin will be pleasing in appearance at all times.

While the plug G is shown as a relatively short member for covering the aperture 43 left at the forward end of the seam formed by the stitches 16, it will be readily understood that it may be made to extend substantially the entire length and width of the shoe, or, if it is so desired, it may be made of such length that it will cover the entire seam formed in the bottom of the vamp. As explained above, the plug G is preferably secured to the vamp by the stitches 21, as well as by cement.

While I have shown and described certain embodiments of my invention, it is to be understood that it is capable of many modifications. Changes, therefore, in the construction and arrangement may be made without departing from the spirit and scope of the invention as disclosed in the appended claims, in which it is my intention to claim all novelty inherent in my invention as broadly as possible, in view of the prior art.

What I regard as new, and desire to secure by Letters Patent, is:

1. A method of forming a moccasin, which method comprises employing a vamp blank having excess material therein, folding the blank in such manner that the excess material forms overlapping portions extending along the bottom of the vamp, cutting through said overlapping portions to form abutting edges in the vamp, and securing said edges to each other to form a seam.

2. A method of forming a moccasin, which method comprises employing a vamp blank having excess material therein, folding the blank over a last in such manner that the excess material forms overlapping portions extending along the bottom of the vamp, cutting through said overlapping portions while the blank is on said last to form abutting edges in the vamp, and se-

curing said edges to each other to form a seam.

3. A method of forming a moccasin, which method comprises employing a vamp blank having excess material therein, folding the vamp blank over a last in such manner that the excess material forms overlapping portions extending along the bottom of the vamp, cutting through at least one of said overlapping portions to form edges extending adjacent each other in the vamp, and securing said edges to each other to form a seam.

4. A method of forming a moccasin, which method comprises employing a vamp blank having excess material therein, folding the vamp blank over a last in such manner that the excess material forms overlapping portions extending along the bottom of the vamp, cutting through said overlapping portions to form abutting edges in the vamp, and securing said edges to each other to form a seam.

5. A method of forming a moccasin, which method comprises employing a vamp blank having excess material therein, assembling said vamp blank with a toe cap and quarters, shaping the assembled structure over a last in such manner that the excess material of the vamp blank forms overlapping portions extending along the bottom of the vamp, cutting through said overlapping portions to form abutting edges in the vamp, and securing said edges to each other.

6. A method of forming a moccasin, which method comprises employing a vamp blank having excess material therein, securing said vamp blank to a toe cap and quarters, shaping the assembled structure in a wet condition over a last in such manner that the excess material forms overlapping portions extending along the bottom of the vamp, tacking said vamp to said last while it is wet to hold said overlapping portions in their overlapping condition until the assembled structure is dry, cutting through said overlapping portions to form abutting edges in the vamp, and securing said abutting edges to each other.

7. A method of forming a moccasin, which method comprises employing a vamp blank having excess material therein, folding the vamp blank over a last in such manner that the excess material forms overlapping portions, cutting through said overlapping portions to form abutting edges in the vamp, securing said edges to each other to form a seam extending substantially longitudinally at the bottom of the vamp, and securing a plug to the inner surface of said vamp to cover the forward end of said seam.

8. A moccasin comprising a vamp having a seam in the bottom thereof, which seam comprises two edges of the vamp stitched

to each other to form a seam extending from the toe to the instep, and a plug secured to the inner side of said vamp at the forward end of said seam.

9. A method of forming a moccasin, which method comprises employing a vamp blank having excess material therein, securing said vamp blank to a front and quarters, shaping the assembled structure in a wet condition over a last in such manner that the excess material forms overlapping portions extending along the bottom of the vamp, securing said vamp to said last while it is wet to hold said overlapping portions in their overlapping condition until the assembled structure is dry, cutting through at least one of said overlapping portions to form abutting edges in the vamp, and securing said abutting edges to each other.

10. A method of forming a moccasin, which method comprises forming a vamp blank having excess material therein, shaping said vamp blank in a wet condition over a last in such manner that the excess material forms overlapping portions extending along the bottom of the vamp, securing said vamp to said last while it is wet to hold said overlapping portions in their overlapping condition until the vamp is dry, cutting through said overlapping portions to form abutting edges in the vamp, and securing said abutting edges to each other.

11. A method of forming a moccasin, which method comprises forming a vamp blank having excess material therein, shaping said vamp blank in a wet condition over a last in such manner that the excess material forms overlapping portions extending along the bottom of the vamp, securing said vamp to said last while it is wet to hold said overlapping portions in their overlapping condition until the vamp is dry, cutting through at least one of said overlapping portions to form abutting edges in the vamp, and securing said abutting edges to each other.

12. A method of forming a moccasin, which method comprises employing a vamp blank having excess material therein, securing said vamp blank to a front and quarters, shaping the assembled structure in a wet condition over a last in such manner that the excess material forms overlapping portions extending longitudinally and substantially centrally along the bottom of the vamp, securing said vamp to said last while it is wet to hold said overlapping portions in their overlapping condition until the assembled structure is dry, cutting through said overlapping portions to form abutting edges in the vamp, and sawing said abutting edges to each other.
